BLOOD LANCET

Tsuneyoshi Sugiyama, Seki, Japan, assignor to Feather
Kogyo Kabushiki Kaisha

Filed Apr. 22, 1974, Ser. No. 462,890

Term of patent 14 years

Int. Cl. D24—02

U.S. Cl. D83—12 R

FIG. 1 FIG. 2 FIG. 3

FIG. 4 FIG. 7

FIG. 5 FIG. 8

FIG. 9

FIG. 6

FIG. 1 is a front view of a blood lancet showing my new design.

FIG. 2 is a rear elevation view.

FIG. 3 is a left side view, the right side being a mirror image thereof.

FIG. 4 is a top plan view.

FIG. 5 is a bottom plan view.

FIG. 6 is a top perspective view.

FIG. 7 is a cross-sectional view of line 7—7 of FIG. 6.

FIG. 8 is a cross-sectional view of line 8—8 of FIG. 6.

FIG. 9 is a cross-sectional view of line 9—9 of FIG. 6.

I claim:

The ornamental design for a blood lancet, as shown and described.
